(57) **CLAIM**

The ornamental design for an annular elastomeric seal for a clutch, as shown and described.

DESCRIPTION

FIG. 1 is a perspective view of an annular elastomeric seal for a clutch according to my new design;

FIG. 2 is a side elevational view, the opposite side view being a mirror image;

FIG. 3 is a front elevational view, the opposite rear view being a mirror image; and,

FIG. 4 is a sectional view taken on line 4—4 of FIG. 1.

1 Claim, 2 Drawing Sheets

FIG. 1

FIG. 2

FIG. 3

FIG. 4
